UNITED STATES PATENT OFFICE.

CLARENCE J. ALFRED, OF NEW YORK, N. Y.

SPOOL-CASE.

No. 900,464.

Specification of Letters Patent.

Patented Oct. 6, 1908.

Application filed June 22, 1908. - Serial No. 439,745.

To all whom it may concern:

Be it known that I, CLARENCE J. ALFRED, a citizen of the United States, and a resident of the city of New York, borough of Manhattan, in the county and State of New York, have invented a new and Improved Spool-Case, of which the following is a full, clear, and exact description.

This invention is an improvement in spool cases, which is designed to form a convenient adjunct for work baskets, work bag and other places where sewing thread is usually kept, and has for its purpose the provision of a spool case of ornamental character, so constructed as to admit of the free withdrawal of the thread but frictionally bind the same and prevent its unwinding except when intentionally pulled out.

The invention further contemplates a shearing cutter in connection with the case, adapted to grip the thread and sever it at the points desired.

In arriving at a case fulfilling these conditions, I make use of two cups or thimbles adapted to telescope together, and when thus assembled to so fit as to bind sufficiently on the thread when passed between them from the spool, as to prevent it from working or passing out until pulled. To one of the thimbles, preferably the end of the smaller one, is attached the shearing cutter, which in the present embodiment of my invention, consists of a lip or tongue stamped or bent outwardly and presenting an approximately right-angle shearing edge which co-operates with a like shearing edge around the opening from which the tongue is stamped to first grip the thread when passed there between and then cut it off, this operation obviously requiring the grasping and pulling of the free end of the thread only.

Reference is to be had to the accompanying drawings forming a part of this specification, in which similar characters of reference indicate corresponding parts in all the views.

Figure 1 is a perspective view of my improved spool case as preferably constructed; Fig. 2 is a plan of the same on an enlarged scale; and Fig. 3 is a central section substantially on the line 3-3 of Fig. 2.

More specifically described, the case proper is composed of two cups or thimbles 5 and 6 respectively, which may be constructed of any suitable sheet material, such, for example, as metal or celluloid. These

thimbles are of such size that when telescoped together, as illustrated in Figs. 1 and 3, sufficient space will be left between them for the passage of the thread from the spool to the outside. This space will, however, not be so large as to admit of the two thimbles dropping apart, but will frictionally bind on the thread and prevent its withdrawal unless purposely pulled, at which time the thread freely unwinds from the spool. The free passage of the thread when drawn out is insured by constructing the bottom inner edge of the larger thimble 5 with a fillet 7, which prevents the telescoping of the two thimbles together to an extent sufficient to bite the thread between the bottom of the larger thimble and the edge of the smaller one, the latter being rounded off, as shown in Fig. 3, in order that the thread will easily slide over it and not be cut.

To the case is suitably attached, preferably at the end of the smaller thimble, a disk 8 which is ordinarily of metal and has a tongue or lip 9, stamped or bent outwardly therefrom and presenting in connection with the edge of the opening from which the tongue is stamped approximately right-angular shearing edges for the thread. The action of the lip or tongue 9 when the thread is inserted under it, is first to firmly grip the same and prevent it from pulling from the spool preparatory to severing it, thus obviously making it unnecessary to grasp the thread at both sides as would be the case in the use of an ordinary cutting edge. The case is ornamental in appearance, and since it completely incloses the thread it keeps it in a clean condition.

While I have shown the cutter made as a separate piece and attached to the case, this will ordinarily be so only when the case is made of celluloid, silver or other material from which an effective cutter could not be made. When, however, the case is made of such material as steel or iron, the tongue 9 will be stamped directly from the thimble.

Having thus described my invention, I claim as new and desire to secure by Letters Patent:

1. A spool case comprising two telescoping thimbles adapted to inclose a spool of thread, said thimbles being of such relative size as to admit of the passage of the thread from the spool between them and provide a frictional engagement therefor.

2. A spool case comprising two telescoping

ing thimbles adapted to inclose a spool of thread, and between which the thread from the spool is adapted to pass outwardly, and a cutter for severing the thread, carried by 5 one of said thimbles.

3. A spool case comprising two telescoping thimbles adapted to inclose a spool of thread, and between which the thread is adapted to pass from the spool to the out- 10 side, the outer of said thimbles having a fillet at the inside of its bottom edge to limit the inward movement of the other thimble.

4. A spool case comprising two telescoping thimbles adapted to inclose a spool of 15 thread, and between which the thread from

the spool is adapted to pass to the outside, the inner edge of the smaller thimble being rounded to permit of the free passage of the thread thereover, and the bottom edge of the larger thimble at the inside filleted to 20 limit the inward movement of the smaller thimble.

In testimony whereof I have signed my name to this specification in the presence of two subscribing witnesses.

CLARENCE J. ALFRED.
